FREQUENCY DISCRIMINATOR

Karl Rath, New York, N. Y., assignor to Radio
Patents Corporation, a corporation of New
York

Application February 14, 1941, Serial No. 378,907

18 Claims. (Cl. 250—20)

The present invention relates to a frequency discriminator or variable frequency response circuit for use in automatic frequency control systems, as a converter or detector in frequency modulation receivers, for frequency monitoring and various other applications requiring means for converting frequency changes, including both the frequency of an alternating current or potential as well as the tuning frequency of a resonant impedance or network, into corresponding amplitude changes of electrical energy.

More particularly the invention is concerned with a frequency discriminator of the phase shift type comprising basically a means for deriving a pair of potentials from a varying frequency, said potentials having a phase relation varying in accordance with the frequency changes to be detected and an electron discharge tube for combining said potentials to produce an output current or voltage having an amplitude varying proportionately to said phase variations, i. e. in turn to the frequency changes to be detected.

In frequency discriminators of the above general type as disclosed for instance in U. S. Patents 2,208,091 to Zakarias and 2,248,197 in the name of the present applicant, difficulties are encountered in certain cases in practice due to the steady or constant plate current supplied by the converter tube upon which is superimposed a variable component being proportional to the frequency changes being converted. Unless this quiescent or steady plate current of the converter is highly stabilized and maintained at a constant value, it is found that the operating point of the converter will be shifted in accordance with fluctuations or ripples of the supply voltage or due to disturbing signals and other causes. In order to reduce the distortion and hum as well as other defects resulting from such shifts of the operating point, adequate smoothing filters are required representing a drawback when price is at a premium.

The present invention has for its object to substantially overcome the above mentioned difficulties in a simple and easy manner by providing a system requiring no steady or quiescent plate current for the conversion of the frequency changes into a current of corresponding amplitude variation.

Other objects and advantages of the invention will become more apparent from the following detailed description taken with reference to the accompanying drawings forming part of this specification, and wherein:

Figure 1 is a circuit diagram of one type of frequency discriminator embodying the principles of the invention.

Figure 2 is a diagram of a modified discriminator of the type according to Figure 1.

Figures 3 and 4 are theoretical diagrams explanatory of the function and operation of the invention.

Figure 5 is a diagram of a frequency discriminator embodying improved features according to the invention.

Figure 6 shows, partly in block diagram form, a discriminator according to the invention embodied as a converter or demodulator in a frequency modulation receiving system, and

Figure 7 is a circuit diagram of a frequency discriminator embodying further features of improvement according to the invention.

Like reference characters identify like parts throughout the different views of the drawings.

Referring more particularly to Figure 1, there is shown a frequency variation response circuit embodying the principles of the invention and comprising a vacuum discharge tube 10 provided

10 with a cathode 11, a first control grid 12, a first positive or screen grid 13, a second control grid 14, a second positive or screen grid 15, and a plate 16; all arranged in the order named with respect to the cathode. Alternating current signals supplied from a source 17 are impressed upon the primary circuit 20 of a double tuned transformer or band pass filter having a resonant secondary circuit 21. As is well known, such a filter represents a phase shift network producing a pair of voltages across the primary and secondary windings whose relative phase angle is dependent upon the relative departure of the tuning frequency to which the circuits 20, 21 are resonant from the frequency of the impressed alternating current supplied by the source 17. Thus, if the impressed frequency equals the resonant frequency of the network, the primary and secondary voltages will be 90° out of phase with respect to each other, while with the impressed frequency departing below or above the resonant frequency of the network the relative phase angle between the primary and secondary voltages will become greater or less than 90° depending upon the frequency departure.

45 The potentials developed by the primary and secondary circuits of the phase shift network are impressed each upon one of the control grids of the tube 10. To this end, in the example shown, the primary 20 is coupled to the grid 14 through 50 a coupling condenser 22 and the secondary 21 is directly coupled to the grid 12 and cathode in a manner well understood. Item 23 represents a biasing network comprising a capacity shunted resistor in the cathode-to-ground lead of the tube 55 to provide suitable grid biasing potential for the grids 12 and 14 which are operated preferably within the negative region of the operating characteristic so as to prevent a positive grid current flow and consequent energy consumption and distortion in the grid circuits. The screen grids 13

and 15 are operated at suitable positive potentials with respect to the cathode as indicated by the plus signs representing high potential sources, and by-passed to ground for alternating currents by means of condensers 24, 25, respectively.

The plate 16 according to the present invention is operated at cathode potential or at negative potential with respect to the cathode by the aid of the network 23. If desirable to bias the plate at a negative potential different from the negative bias of the control grids 12 and 14, an additional biasing source may be provided in the plate circuit as will be understood.

In a tube of the aforescribed type a concentrated electron space charge or virtual cathode will be formed in the region between the screen grid 15 and the plate 16 by virtue of the accelerating action of the screen grid 15 on the electron stream and the subsequent retarding or repelling action of the negative field produced by the plate 16. Thus, electrons having passed the screen 15 will be repelled by the plate 16 and if the latter is at a sufficiently negative potential so as to substantially prevent a steady electron current flow through the external plate circuit, the electrons will be returned and form a region of increased charge density known as a virtual cathode adjacent to and at a spacing distance from the plate. The intensity or charge density of this virtual cathode will vary in phase with the fluctuations of the electron stream emitted from the cathode, that is in phase with both signal potentials applied to the control grids 12 and 14. Accordingly, due to this dual control the space charge in front of the plate 16 will vary in accordance with the vectorial sum of the control grid potentials as will be further understood from the following with reference to the theoretical diagrams shown in Figures 3 and 4.

If the impressed frequency is equal to the resonant frequency of the phase shift network 20, 21, the potentials e_1 on one control grid and e_2 on the other control grid will be 90° out of phase as pointed out above. The vectorial resultant e_r will have a value as shown in the diagram. If the frequency of the impressed potential varies in either sense relative to the resonant frequency of the phase shift network, the relative phase of the potential e_2 with respect to e_1 will become greater or less than 90° as shown at e_2' and e_2'' , respectively, producing a resultant fluctuation of the space charge e_r' and e_r'' , respectively, of different amplitude depending on the relative phase angle displacement between the control potentials. The potential e_2 not only varies in phase depending on the departure of the impressed frequency from the resonant frequency of the transformer 20, 21, but also in amplitude in that the end of the potential vector e_2 travels along a circle in a manner well known and shown in Figure 3. Thus, for extreme detuning the potential e_2 may be neglected and the space charge will fluctuate in accordance with e_1 only and detailed investigation shows that the resultant e_r varies according to a curve as shown in Figure 4 as a function of the relative phase angle between the potentials e_1 and e_2 ; that is, in turn of the relative departure of the impressed frequency from the resonant frequency of the network 20, 21. Curve e_r is not symmetrical with respect to the line representing the potential e_1 as shown in the diagram and accordingly by suitably adjusting the resonant frequency of the network 20, 21 in relation to the particular (center, carrier) frequency the relative deviations from

which are to be detected or translated (point P), a maximum swing or range d of output current variation may be realized. The slope of the curve e_r representing the conversion efficiency of the frequency change into amplitude change is dependent on the changes of the phase angle as a function of the detuning between the impressed frequency relative to the resonant frequency of the network 20, 21; that is, on the "Q" value

$$(w_R^L)$$

or damping coefficient of the resonant or phase shift network. Thus, in case of low damping or high "Q," the slope of the curve will be steeper (e_r) than in the case of high damping or a low "Q" (curve e_r') of the network or other resonant impedance means as indicated in the diagram.

From the foregoing it is seen that the tube functions in the first place by converting frequency changes into an amplitude modulated space charge adjacent to the plate or output electrode.

Due to the fluctuations of the space charge or virtual cathode adjacent to the plate 16 at the rate of the input frequency and at amplitudes varying according to the diagram shown in Figure 4, a corresponding displacement current will be induced in the external plate circuit. This current representing an amplitude modulated signal is caused to develop a corresponding voltage by means of a resonant transformer included in the plate circuit comprising a tuned primary 26 and a secondary 27. This voltage is rectified in any suitable manner such as by the aid of a diode rectifier structurally embodied in the tube 10. For the latter purpose the anode 28 of the diode cooperating with the common cathode 11 in a known manner is connected to the high potential side of the transformer secondary 27 in series with a load resistance 30 by-passed by a condenser 31 whereby an output voltage will be developed by said resistance varying in amplitude according to the amplitude changes of the induced displacement current in the plate circuit i. e. in turn in accordance with the initial frequency changes to be detected. The detected voltage may be further amplified or directly applied to a utilization circuit or translating device connected to terminals $a-b$ in the drawing. The primary and secondary of the input and output transformers should be carefully shielded to prevent undesirable spurious couplings and interference liable to cause additional phase shifts and impairment of the stability and accuracy of the frequency conversion. Since the displacement current induced in the external plate circuit by the varying space charge adjacent to the plate 16 is proportional to the rate of change of the charge density, there is provided in Figure 1 a by-pass condenser 29 across the diode rectifier designed to equalize the increased induced currents for the higher frequency components, especially when the system serves as a detector for wide band frequency modulated signals. In case of a discriminator for frequency control or stabilization or for frequency monitoring, condenser 29 may be dispensed with.

From the foregoing it is seen that there is provided by the invention a frequency discriminator of the type using an electron discharge stream for producing a discriminating voltage or current, wherein no steady or quiescent output current is required. As a result, the effect of a

fluctuating supply voltage and other disturbances in displaying the center or zero operating point of the system are substantially eliminated by the invention. The invention also completely eliminates the necessity of a special balancing voltage required in previous systems utilizing a steady plate current to obtain a zero response for the center or carrier frequency as desired in automatic frequency control or monitoring devices.

It will be further evident that the invention may be employed for converting frequency changes of an alternating current or potential into corresponding amplitude changes in which case the source 17 supplies a signal of varying frequency (fluctuating carrier in case of automatic frequency control, frequency modulated radio wave, etc.) while the phase shift network is resonant to a fixed frequency (center or carrier frequency). Alternatively, the system may serve for translating changes of the resonant frequency of a circuit or network into corresponding current changes in which case the source 17 represents a constant frequency oscillator (crystal oscillator, etc.), while the tuning frequency of the network 20, 21 is varied by either changing the effective capacity or inductance of the circuit, whereby these changes will be translated into corresponding changes of electric current in the output circuit.

Referring to Figure 2, there is shown a discriminator similar to Figure 1 but differing from the latter in the manner of effecting the variable phase shift of the control potentials on the grids 12 and 14. The grid 12 is directly connected to the source of input signals 17 to cause an initial variation of the electron space current in accordance with the input frequency (e_1). The control grid 14 is externally decoupled from the input circuit and from the remaining parts of the system and connected to ground or cathode through a resonant impedance means such as a parallel tuned circuit 32. In the same manner that a concentrated space charge or virtual cathode is formed between the accelerating grid 15 and the decelerating plate 16, a similar virtual cathode will be formed between the accelerating grid 13 and the decelerating grid 14. This latter virtual cathode will cause a displacement current to flow through the external circuit of the grid 14 containing resonant circuit 32 carefully shielded from the remaining parts of the system by means of a screen 32'. The latter represents a varying impedance depending on frequency and consequently the voltage developed by it, constituting the control for the grid 14, will vary in phase relative to the space charge fluctuations or potential on the grid 12 in dependence upon the relative frequency departure of the resonant frequency of the circuit 32 from the input signal frequency. Since the induced displacement current varies in accordance with the rate of change of the space charge fluctuations it will be 90° out of phase with the latter and in case that the impressed frequency equals the resonant frequency of the circuit 32, the latter will offer pure ohmic impedance to the displacement current resulting in a control potential (e_2) on grid 14 being 90° dephased with respect to the control potential (e_1) on the grid 12. If the impressed frequency deviates in either sense from the resonant frequency of the circuit 32, the latter will offer either capacitative or inductive impedance to the displacement current and the normal 90° phase angle will be

either increased or decreased in substantially the same manner as shown in Figure 3. Accordingly, therefore, the second space charge or virtual cathode formed between the accelerating grid 15 and the plate 16 will vary according to resultant e_2 in substantially the same manner as in the case of Figure 1 and a similar operating characteristic will be obtained as shown in Figure 4. The rest of the circuit is substantially similar to that of Figure 1 as will be readily understood.

The system according to Figure 2 is especially suited for translating capacity or inductance changes into corresponding current changes. For this purpose it is only necessary to provide a variable inductance or capacity to form an effective tuning element of the circuit 32 and by using a circuit with a high "Q" value as determined by the range of inductance or capacity changes to be converted, slight or minute changes of capacity or inductance may be directly translated into substantial changes of current by means of a single tube, where with the standard amplifiers a plurality of stages would be required to obtain a corresponding plate current swing for the same input changes.

Figure 5 shows a discriminator circuit according to the invention, wherein the tube is utilized both for converting the frequency changes into amplitude changes as well as an amplifier for the converted or output energy. For this purpose a portion of the output voltage developed by the resistor 30 is fed back upon the grid 12, whereby the cathode 11, control grid 12 and screen grid 13 will function as a triode amplifier by the provision of a suitable load impedance such as a low-pass network comprising a resistance 33 bypassed to ground by a condenser 34 included in the external screen circuit. The voltage developed by the resistor 33 which in the case of a frequency modulated input signal supplied by the source 17 will vary in accordance with the audio or modulation signal may be directly applied to the output terminals *a*, *b* for further amplification and energizing a suitable translating device such as a loud speaker. Alternatively, the potential at modulating frequency developed on the screen 13 may be impressed by way of a coupling condenser 37 upon control grid 14 to cause additional variations of the electron stream developed in the circuit of the screen grid 15 by the provision of a further load impedance comprising resistor 35 and by-pass condenser 36. The voltage developed by the resistor 35 may serve for further utilization in a subsequent circuit or device connected to the terminals *a*, *b*. In an arrangement of this type, the controls by the grids 12 and 14 by the audio or modulation potential are in opposite phase. However, the control by the grid 14 will substantially exceed the control of grid 12 so as to secure substantial amplification while at the same time improving the stability of the system on account of the differential action of the control potentials.

Referring to Figure 6, there is shown, partly in block diagram form, a complete frequency modulation receiving system embodying a frequency converter in accordance with the invention. Frequency modulated radio signals intercepted by an antenna such as a dipole 40, 40' are passed through a radio frequency amplifier 41 and combined in a mixer 42 with local oscillations generated by an oscillator 43 to produce signal waves of intermediate frequency. The latter are further amplified in an intermediate frequency amplifier 44 and passed through a limiter 45 of

known design to remove spurious amplitude modulation. The frequency modulated potential supplied by the limiter 45 is impressed upon the grid 12 of the converter 10 of the type described in connection with Figure 2. In contrast to the latter, wherein the amplitude modulated waves in the plate circuit are detected by means of a diode rectifier embodied in the same tube, the output signal in Figure 6 is impressed upon the diode circuit of a composite screen grid-diode audio amplifier tube 46 by way of a tuned transformer comprising a primary 26' and tuned secondary 27'. The tube 46 is provided with a cathode 47, a control grid 48, screen grid 49 and a plate or anode 50 and a diode anode 51 arranged in cooperative relation to the common cathode 47. The diode circuit includes a load resistor 52 and a grid biasing network 53 is inserted in the cathode to ground lead of the tube. Rectified potential is derived from the load resistor 52 by way of a series network comprising a condenser 54 and resistor 55 and impressed upon the control grid 48 to produce amplified rectified voltage across load resistor 56 in the plate circuit by-passed to ground by condensers 57 and 58. The amplified audio voltage is impressed upon a further audio amplifier 59 energizing a loud speaker 60.

Referring to Figure 7, there is shown a composite frequency-converter-amplifier according to the invention especially suited for translating slow or progressive frequency variation or for indicating tuning or frequency deviations from a predetermined value for use as a frequency, capacity, inductance deviation meter or frequency monitor and other applications. Signal waves supplied from a source of varying or constant frequency are impressed by way of resonant input circuit 21 upon the grid 12 and cathode of the tube in a manner similar to that described hereinbefore. If the range of frequency is limited or if only deviations from a particular frequency are to be determined as in the case of automatic frequency control or frequency monitoring systems, the "Q" of the resonant circuit may be chosen extremely high resulting in a corresponding narrowing of the straight line operating portion (d according to Figure 4) and considerably increased slope or conversion efficiency from frequency to amplitude change. For this purpose, there is shown in Figure 7 a piezo-electric crystal 61 employed as a resonant impedance means connected between control grid 14 and ground and by-passed for direct current through a portion of load resistance 65 and potentiometer 63 connected across the high voltage supply source. If desirable a separate D. C. by-pass or cathode return may be provided in the form of a high ohmic resistance 62 or the equivalent shunted across the crystal. A portion of the converted voltage developed by the resistor 39 in the diode circuit is impressed upon the grid 12 of the tube for further amplification in a manner substantially similar to that shown in Figure 5. Screen grid 13 is connected to the positive pole of the supply source through a voltage reducing resistance 64 and to the negative pole of said source through a load resistance 65 by-passed to ground by condenser 66 to develop amplified potential varying according to the frequency changes to be detected and converted. Accordingly, a meter 68 connected in the circuit of the screen grid 13 will indicate instantly the deviation of the input frequency from the resonant frequency of the crystal 61 and in view of the high

"Q" of the crystal 61 and the additional amplification of the direct current output voltage, extreme response sensitivities are obtained enabling the indication of deviations as low as a single cycle from frequencies of the order of one megacycle and more. If desired, the potential developed in the circuit of screen grid 13 may be impressed upon the control grid 14 by connecting the latter to a suitable tap point of the load resistance 65. By connecting the cathode or ground to an intermediate point of the potentiometer 63 there is provided a negative potential applied to the control grid 14 for compensating the positive potential due to its direct or conductive connection with the screen grid 13. The resultant controls by both grids 12 and 14 which as in Figure 5 are again in opposite phase and the final variation may be indicated in the external circuit of the screen grid 15 by the provision of a meter 67 or may be otherwise utilized by the provision of a suitable load impedance supplying a potential for control of the tuning reactance in an automatic frequency control system or any other purpose as will be understood. In place of using a pair of separately biased screen grids, a common screen grid 15 may be provided extending over both sides of the control grid 14 as shown in Figure 6 and additional suppressor and other electrodes may be included in the tube in a manner well known in the art.

It will be evident from the foregoing that the invention is not limited to the specific circuits and arrangement of parts shown and disclosed herein for illustration, but that the underlying principle and novel thought are susceptible of numerous modifications and variations coming within the broad spirit of the invention as defined in the appended claims. The specification and drawings are accordingly to be regarded in an illustrative rather than a limiting sense.

I claim:

1. A frequency discriminator comprising an electron discharge tube provided with a cathode, a pair of control electrodes and a output electrode, a source of high frequency waves, phase shifting means for deriving from said source a pair of control potentials having a relative phase varying in accordance with the relative departure of the frequency of said waves from a predetermined frequency, means to substantially prevent a steady electron current flow to and to produce a concentrated electron space charge near said output electrode, means for applying each of said control potentials to one of said control electrodes to cause said space charge to fluctuate in accordance with the vectorial sum of said control potentials, an external circuit connected to said output electrode and cathode including load impedance means adapted to develop high frequency output energy, and amplitude modulation detecting means for demodulating said output energy.

2. A frequency discriminator comprising an electron discharge tube provided with means for producing an electron space current, means for producing a concentrated electron space charge in said tube, a source of high frequency waves, means including circuit connections from said source to said tube for affecting a first control of said electron space current in accordance with said high frequency waves, further control means excited from said source including phase shifting means for affecting additional control of said space current in accordance with said high frequency waves.

quency waves at a phase varying relative to the first control phase in dependence upon the relative departure of the frequency of said waves from a predetermined frequency to cause fluctuations of said space charge in accordance with the vectorial sum of both said controls, an output electrode adjacent to said space charge biased to prevent any steady electron current flow thereto, an external circuit connected to said output electrode including load impedance means adapted to develop high frequency output energy, and amplitude modulation detecting means for demodulating said output energy.

3. A frequency discriminator comprising an electron discharge tube provided with means for producing an electron space current and a first and second control grid disposed at different points in the path of said space current, a source of high frequency waves, means for applying potential from said source to said first grid, further means including phase shifting means for exciting said second grid by potential from said source at a phase varying relative to the potential applied to said first grid in accordance with the relative departure of the frequency of said waves from a predetermined frequency, an output electrode within said tube, means including biasing means for said output electrode to substantially prevent a steady electron current flow to and to produce a concentrated electron space charge in the vicinity of said output electrode, and an external circuit connected to said output electrode including load impedance means adapted to develop high frequency output energy, and amplitude modulation detecting means for demodulating said output energy.

4. A frequency discriminator comprising an electron discharge tube provided with a cathode, a first and a second control grid and a plate arranged substantially in the order named, and at least one positively biased screen grid located between said second control grid and plate, means for negatively biasing said plate relative to said screen grid to substantially prevent a steady electron current flow to and to produce a concentrated electron space charge in the vicinity of said plate, a source of high frequency waves, means including phase shifting means for exciting both said control grids from said source at a relative phase varying in accordance with the relative departure of the frequency of said waves from a predetermined frequency, an external circuit connected to said plate including load impedance means adapted to develop high frequency output energy, and amplitude modulation detecting means for demodulating said output energy.

5. A frequency discriminator comprising an electron discharge tube provided with a cathode, a first and a second control grid and a plate arranged substantially in the order named, and at least one positively biased screen grid located between said second control grid and said plate, means for negatively biasing said plate relative to said screen grid to substantially prevent a steady electron current to and to produce a concentrated electron space charge in the vicinity of said plate, a source of high frequency waves, means for impressing potential from said source upon said first control grid, resonant impedance means tuned to a predetermined frequency, the relative frequency of said waves with respect to the tuning frequency of said impedance means being variable, means for reactively exciting said second grid from said source by way of said

resonant impedance means, whereby the relative phase of the exciting potential on said second grid will vary in proportion to the relative departure of the frequency of said waves from the tuning frequency of said impedance means, an external circuit including a load impedance adapted to develop high frequency output energy connected to said plate, and amplitude modulation detecting means for demodulating said output energy.

6. A frequency discriminator comprising an electron discharge tube provided with a cathode and a first and a second control grid, a plate arranged in the order named, a first positively biased screen grid located between said second control grid and said plate, and a second positively biased screen grid located between said first and second control grids, means for negatively biasing said plate relative to said first screen grid to substantially prevent a steady electron current flow to and to produce a concentrated electron space charge in the vicinity of said plate, a source of high frequency waves, means including phase shifting means for exciting both said control grids from said source at a relative phase varying in accordance with the relative departure of the frequency of said waves from a predetermined frequency, an external circuit connected to said plate including load impedance means adapted to develop high frequency output energy, and amplitude modulation detecting means for demodulating said output energy.

7. A frequency discriminator comprising an electron discharge tube provided with a cathode, a first and a second control grid and a plate, a first positively biased screen grid located between said second control grid and said plate, a second positively biased screen grid located between said first and second control grids, means for negatively biasing said plate relative to said screen grid to substantially prevent a steady electron current flow to and to produce a concentrated electron space charge near to said plate, a source of high frequency waves, means for impressing potential from said source upon said first control grid, resonant impedance means tuned to a predetermined frequency, the relative frequency of said source with respect to the tuning frequency of said impedance means being variable, means for reactively exciting said second control grid from said source by way of said impedance means, whereby the relative phase of the control potential on said second control grid with respect to the control potential on said first control grid will vary in proportion to the relative departure of the frequency of said waves from the tuning frequency of said impedance means, an external circuit connected to said plate including load impedance means adapted to develop high frequency output energy, and amplitude modulation detecting means for demodulating said output energy.

8. A frequency discriminator comprising an electron discharge tube provided with a cathode, a pair of control grids and a plate arranged in the order named, a first positively biased screen grid located between said control grids, a second positively biased screen grid located adjacent to said plate, a source of high frequency waves, means for impressing potential from said source upon one of said control grids, resonant impedance means connected between said other control grid and said cathode, whereby said last mentioned control grid is excited from said source by space charge coupling with the electron space

current through said tube at a phase varying in accordance with the relative frequency departure of said waves from the resonant frequency of said impedance means, means for biasing said plate negatively with respect to said second screen grid to substantially prevent a steady electron current flow to and to produce a concentrated electron space charge in the vicinity of said plate, an external circuit connected to said plate including load impedance means adapted to develop high frequency output energy, and amplitude modulating detecting means for demodulating said output energy.

9. A frequency discriminator comprising an electron discharge tube provided with a cathode, a first and second control grid and a plate arranged in the order named, at least one positively biased screen grid located between said second control grid and said plate, means for negatively biasing said plate relative to said screen grid to substantially prevent a steady electron current flow to and to produce a concentrated electron space charge in the vicinity of said plate, a source of high frequency waves, means including phase shifting means for exciting both said control grids from said source at a relative phase varying in accordance with the relative departure of the frequency of said waves from a predetermined frequency, an external high frequency load circuit including amplitude modulation detecting means connected to said plate, further means for impressing demodulated potential from said load circuit upon one of said control grids, and load impedance means inserted in the external circuit of said screen grid adapted to develop demodulated output energy.

10. A frequency discriminator comprising an electron discharge tube provided with a cathode, a pair of control grids and a plate arranged in the order named, a first positively biased screen grid located between said control grids, a second positively biased screen grid located adjacent to said plate, a source of high frequency waves, means for impressing potential from said source upon one of said control grids, resonant impedance means connected between said other control grid and said cathode, whereby said last mentioned control grid is excited from said source by space charge coupling with the electron space current through said tube at varying phase in accordance with the relative frequency departure of said waves from the resonant frequency of said impedance means, means for biasing said plate negatively with respect to said second screen grid to substantially prevent a steady electron current flow to and to produce a concentrated electron space charge in the vicinity of said plate, said space charge varying according to the vectorial sum of the potentials upon said control grids an external circuit connected to said plate including load impedance means adapted to develop high frequency output energy amplitude modulation detecting means for demodulating said output energy, means to impress demodulated potential from said external circuit upon one of said control grids, and load impedance means inserted in the external circuit of said first screen grid adapted to develop demodulated output energy.

11. A frequency discriminator comprising an electron discharge tube provided with a cathode, a pair of control grids and a plate arranged in the order named, a first positively biased screen grid located between said control grids, a second positively biased screen grid located adjacent

said plate, a source of high frequency waves, means for impressing potential from said source upon one of said control grids, resonant impedance means connected between the other control grid and said cathode, whereby said last mentioned control grid is excited from said source by space charge coupling with the electron space current through said tube at varying phase in accordance with the relative frequency departure of said waves from the resonant frequency of said impedance means, means for biasing said plate negatively with respect to said second screen grid to substantially prevent a steady electron current flow to and to produce a concentrated electron space charge in the vicinity of said plate, said space charge varying according to the vectorial sum of the potentials upon said control grids, an external circuit connected to said plate including load impedance means adapted to develop high frequency output energy amplitude modulation detecting means for demodulating said output energy, means to impress demodulated potential from said external circuit upon said first grid, load impedance means inserted in the external circuit of said first screen grid to develop amplified demodulated potential, a coupling connection from said last load impedance to said second control grid, and further load impedance means in the external circuit of said first screen grid adapted to develop demodulated output energy.

12. A frequency discriminator comprising an electron discharge tube provided with means for producing a concentrated electron space charge, means for subjecting said space charge to a dual control in accordance with a common high frequency input wave at a varying relative phase in accordance with the relative frequency departure of said wave from a predetermined frequency, an output electrode in the vicinity of said space charge biased so as to substantially prevent a steady electron current thereto, an external circuit connected to said output electrode including load impedance means adapted to develop high frequency output energy, and amplitude modulation detecting means for demodulating said output energy.

13. A frequency discriminator comprising an electron discharge tube provided with a cathode, a pair of control electrodes and an output electrode, a source of high frequency waves, phase shifting means for deriving from said source a pair of control potentials having a relative phase varying in accordance with the relative departure of the frequency of said waves from a predetermined frequency, means to substantially prevent a steady electron current flow to and to produce a concentrated electron space charge near said output electrode, means for applying each of said control potentials to one of said control electrodes to cause said space charge to fluctuate in accordance with the vectorial sum of said control potentials, an external circuit connected to said output electrode including load impedance means adapted to develop high frequency output energy, amplitude modulation detecting means for demodulating said output energy, and equalizing means to compensate for the increase of the current induced in said external circuit by said space charge as a function of frequency.

14. A frequency discriminator comprising an electron discharge tube provided with a cathode, a pair of control electrodes and an output electrode, a source of high frequency waves, phase shifting means for deriving from said source a

pair of control potentials having a relative phase varying in accordance with the relative departure of the frequency of said waves from a predetermined frequency, means to substantially prevent a steady electron current flow to and to produce a concentrated electron space charge near said output electrode, means for applying each of said control potentials to one of said control electrodes to cause said space charge to fluctuate in accordance with the vectorial sum of said control potentials, an external circuit connected to said output electrode including load impedance means adapted to develop high frequency output energy, and a rectifying circuit coupled to said load impedance means including a by-pass condenser to compensate for the increase of the current induced in said external circuit by said space charge as a function of frequency.

15. A frequency discriminator comprising an electron discharge tube provided with a cathode, a first control grid, a first screen grid, a second control grid, a second screen grid and a plate, all arranged substantially in the order named, means for maintaining said control grids and said plate at relatively low and for maintaining said screen grids at relatively high steady potentials with regard to said cathode to produce a pair of concentrated space charge regions adjacent to said second control grid and said plate, respectively, and to substantially prevent a steady electron current to said plate, a source of high frequency signal energy, resonant impedance means, the relative frequency of said energy with respect to the resonant frequency of said impedance means being variable, means for impressing potential from said source upon said first control grid, said resonant impedance means being connected between said second control grid and said cathode to develop control potential at signal frequency upon said second control grid having a phase varying in relation to the phase of the potential upon said first control grid in dependence upon the relative frequency departure of said signal energy from the resonant frequency of said impedance means, an external circuit connected to said plate and cathode including load impedance means adapted to develop high frequency output energy, and amplitude modulation detecting means for demodulating said output energy.

16. A frequency discriminator comprising an electron discharge tube provided with a cathode, a first control grid, a first screen grid, a second control grid, a second screen grid and a plate, all arranged substantially in the order named, means for maintaining said control grids and said plate at relatively low and for maintaining said screen grids at relatively high steady potentials with respect to said cathode to produce a pair of concentrated space charge regions adjacent to said second control grid and said plate, respectively, and to substantially prevent a steady electron current to said plate, a source of high frequency signal energy of varying frequency, resonant impedance means tuned to predetermined fixed frequency, means for impressing potential from said source upon said first control grid, said resonant impedance means being connected between said second control grid and said cathode to develop control potential at signal frequency upon said second control grid having a phase varying in relation to the phase of the potential upon said first control grid in de-

pendence upon the frequency changes of said signal energy, an external circuit connected to said plate and cathode including load impedance means adapted to develop high frequency output energy and amplitude modulation detecting means for demodulating said output energy.

17. A frequency discriminator comprising an electron discharge tube provided with a cathode, a first control grid, a first screen grid, a second control grid, a second screen grid and a plate, all arranged substantially in the order named, means for maintaining said control grids and said plate at relatively low and for maintaining said screen grids at relatively high steady potentials with respect to said cathode to produce a pair of concentrated space charge regions adjacent to said second control grid and to said plate, respectively, and to substantially prevent a steady electron current to said plate, a source of high frequency signal energy subject to frequency deviations from a predetermined frequency, resonant impedance means tuned to said predetermined frequency, means for impressing potential from said source upon said first control grid, said resonant impedance means being connected between said second control grid and said cathode to develop control potential at signal frequency upon said second control grid having a phase varying in either sense from a normal phase position in dependence upon the sense and magnitude of deviation of the signal frequency from said predetermined frequency, an external circuit connected to said plate and cathode including load impedance means adapted to develop high frequency output energy, and amplitude modulation detecting means for demodulating said output energy.

18. A frequency discriminator comprising an electron discharge tube provided with a cathode, a first control grid, a first screen grid, a second control grid, a second screen grid and a plate, all arranged substantially in the order named, means for maintaining said control grids and said plate at relatively low and for maintaining said screen grids at relatively high steady potentials with respect to said cathode to produce a pair of concentrated space charge regions adjacent to said second control grid and said plate, respectively, and to substantially prevent a steady electron current to said plate, a source of high frequency signal energy subject to frequency deviations from a predetermined frequency, resonant impedance means tuned to said predetermined frequency, means for impressing potential from said source upon said first control grid, said resonant impedance means being connected between said second control grid and said cathode to develop control potential upon said second control grid having a phase varying in sense and magnitude relative to a normal phase position in dependence upon the direction and magnitude of deviation of the signal frequency from said predetermined frequency, an external circuit connected to said plate and cathode including load impedance means adapted to develop high frequency output energy, amplitude modulation detecting means for demodulating said output energy, further means for impressing potential derived from the demodulated energy upon said first control grid, and further load impedance means connected in the circuit to said first screen grid to develop amplified demodulated energy.
